PARKING SIGNAL STANDARD

Jerry C. Moore, 5018 Pershing, Houston, Tex. 77033

Filed Jan. 8, 1970, Ser. No. 20,825

Term of patent 14 years

Int. Cl. D29—99

U.S. Cl. D72—1

Fig. 2

Fig. 1

Fig. 3

Fig. 4

FIG. 1 is a side elevational view of a parking signal standard embodying my new design;

FIG. 2 is a plan view thereof;

FIG. 3 is a front elevational view thereof the rear appearing identical; and

FIG. 4 is an isometric view of the front and side thereof, the rear and other side appearing identical.

The flag is shown in broken lines in FIGS. 1, 3, and 4 for illustrative purposes only.

I claim:

The ornamental design for parking signal standard, as shown and described.
